[57] CLAIM

The ornamental design for a syringe having a detachable plunger rod, as shown and described.

DESCRIPTION

FIG. 1 is an exploded perspective view of a syringe having a detachable plunger rod showing our new design; FIG. 2 is a side elevational view of the syringe and plunger of FIG. 1;

FIG. 3 is a side elevational view of the syringe and plunger when the syringe and plunger are rotated 90° from their position shown in FIG. 2;

FIG. 4 is a top plan view of the syringe and plunger;

FIG. 5 is a bottom plan view of the syringe and plunger; FIG. 6 is a side elevational view of the plunger rod shown separately for clarity of disclosure;

FIG. 7 is a side elevational view thereof, rotated 90° from its position in FIG. 6;

FIG. 8 is a top plan view thereof;

FIG. 9 is a bottom plan view thereof; and,

FIG. 10 is an exploded fragmentary side elevational view of the syringe, plunger, and plunger rod without the plunger rod being inserted in the plunger.
